Specification for Design.

Patented Jan. 4, 1921.

Application filed May 19, 1920. Serial No. 382,607. Term of patent 14 years.

To all whom it may concern:

Be it known that I, JOHN J. JONES, a citizen of the United States, residing at Buffalo, in the county of Erie and State of New York, have invented a new, original, and ornamental Design for a Bathtub, of which the following is a specification, reference being had to the accompanying drawing, forming part thereof.

Figure 1 is a side view of a bath tube

showing my new design. Fig. 2 is a longitudinal section of the same. Fig. 3 is a top plan view of the same. Fig. 4 is a fragmentary vertical transverse section taken on line 4—4, Fig. 1.

I claim:

The ornamental design for a bathtub, as shown.

JOHN J. JONES.
